(57) **CLAIM**

The ornamental design for a hair curling wand, as shown and described.

DESCRIPTION

FIG. 1 is a right side elevational view of a hair curling wand showing my new design;

FIG. 2 is a rear elevational view thereof;

FIG. 3 is a left side elevational view thereof;

FIG. 4 is a front elevational view thereof;

FIG. 5 is a top plan view thereof;

FIG. 6 is a bottom plan view thereof;

FIG. 7 is a rear perspective view thereof; and,

FIG. 8 is a front perspective view thereof.

In the drawings, the broken lines illustrate portions of the hair curling wand which form no part of the claimed design.

1 Claim, 5 Drawing Sheets
